Des. 193,942
Patented Oct. 30, 1962

193,942

HOLDER FOR A FLOWER POT OR THE LIKE

Donald R. Wagnitz, 737 N. Michigan Ave., Chicago, Ill.

Filed Sept. 28, 1961, Ser. No. 66,900

Term of patent 3½ years

(Cl. D35—3)

FIG. 1

FIGURE 1 is a side elevational view of a holder for a flower pot or the like showing my new design; and

The broken line representation of a flower pot in the views is for purposes of illustration only.

I claim:

The ornamental design for a holder for a flower pot or the like, as shown and described.
